UNITED STATES PATENT OFFICE.

CHARLES BARTSCH, OF NEW YORK, N. Y.

CLOTHES-LINE FASTENER.

SPECIFICATION forming part of Letters Patent No. 581,248, dated December 18, 1894.

Application filed August 14, 1894. Serial No. 520,242. (No model.)

To all whom it may concern:

Be it known that I, CHARLES BARTSCH, of New York city, New York, have invented an Improved Clothes-Line Fastener, of which the following is a specification.

This invention relates to an improved fastener for connecting the two ends of a clothes line and which permits the line to be readily tightened or slackened.

10 In the accompanying drawings: Figure 1 is a side view of my improved fastener showing it open. Fig. 2 is a longitudinal section on lines 2, 2, Figs. 3 and 4 showing it closed. Fig. 3 is a bottom view of the fastener, and

15 Fig. 4 an end view thereof.

The letter a , represents the tubular body or shell of the fastener provided at one end with a perforated socket a' , for receiving the knotted end A, of the clothes line B. At the 20 opposite end the shell a , is slotted and provided with downwardly projecting lugs a^2 , that constitute the bearings for the pivot b , of the clamping lever c . This lever is made of the peculiar form shown in Fig. 1, that

25 is to say it is provided with an eccentric nose c' , at one end and with a serrated dog c^2 , at

the opposite end, which projects at about right angles to said nose. The nose c' , is adapted to press the line B against a serrated section a^3 , formed on the inner wall of the shell a , while the dog c^2 is adapted to press said line against a curved shoulder a^4 , of socket a' . In this way a double grip is obtained which securely locks the free end of the line B, to the fastener.

In order to slacken or remove the line the lever c , is swung down (Fig. 1) when both the dog c^2 , and the eccentric nose c' , will release the line and permit it be withdrawn.

What I claim is—

The combination of a slotted tubular shell having an inner serrated surface a^3 and a jam shoulder a^4 , with a clamping lever provided with a cam c' , and a serrated dog c^2 , placed at about right angles, and adapted to co-operate with the surface a^3 , and shoulder a^4 , respectively, substantially as specified.

CHARLES BARTSCH.
